UNITED STATES PATENT OFFICE.

HARRY A. VAN VLECK, OF PARSONS, KANSAS.

MIXING DEVICE.

Application filed August 2, 1921. Serial No. 489,325.

To all whom it may concern:

Be it known that I, HARRY A. VAN VLECK, a citizen of the United States, residing at Parsons, in the county of Labette and State 5 of Kansas, have invented new and useful Improvements in Mixing Devices, of which the following is a specification.

This invention relates to attachments for internal combustion engines, particularly to 10 mixing devices, and has for its object the provision of a device adapted to be interposed between a carbureter and the intake manifold of an engine whereby to break up the gasoline vapor and thereby render it 15 more highly explosive and consequently more efficient as a fuel.

An important and more specific object is 20 the provision of a device of this character which is formed as a gasket adapted to be clamped between the flanged meeting ends 25 of the carbureter and intake manifold, the gasket carrying a fine wire screen of peculiar shape through which the gasoline vapor passes and by means of which the vapor is broken up and a more intimate 30 commingling of the gasoline vapor and air effected.

An additional object is the provision of 35 a device of this character which will be simple and inexpensive in manufacture, highly efficient in use, durable in service, and a general improvement in the art.

With the above and other objects and advantages in view, the invention consists in 35 the details of construction to be hereinafter more fully described and claimed and illustrated in the accompanying drawings in which

Figure 1 is an elevation of my device, 40 Figure 2 is a longitudinal sectional view therethrough, and

Figure 3 is a cross sectional view.

Referring more particularly to the drawings, I have shown my device as comprising 45 a pair of gaskets 10 of a size and shape to fit between the flanged ends of a carbureter and intake manifold, the ends of the gaskets being formed with holes 11 for the passage of the usual bolts, not shown, employed for 50 holding the flanged ends together. These gaskets are of course provided with openings 12 at their centers for the passage of the mixture. Disposed between the two gaskets is a circular piece of wire screen 13 55 which does not extend to the outer edges of

the gaskets and the gaskets are cemented or otherwise secured together outwardly of the edge of the screen 13. Within the openings 12 the portion of the screen 13 exposed is peculiarly formed. At this point the screen 60 is pressed into angular shape, as shown, whereby it will be V-shaped in cross section with the vertex of the V formed as a ridge 14 which faces toward the current of mixture. This pressing of the screen results in 65 providing inclined surfaces 15 which of course diverge from the ridge 14.

When my device is inserted between the carbureter and intake manifold of the engine it is apparent that when the current 70 of mixture strikes against the screen it will be most efficiently broken up, the gasoline being more intimately commingled with the air whereby a more explosive fuel will be provided which will greatly improve the 75 running of the engine. This V-shaped screen does away with the use of all splitting bars or anything else that might be placed in the center of the vaporizer to break and spread the gas.

Having thus described my invention, I claim:

1. A device of the character described comprising a gasket adapted to be secured between the flanged meeting ends of the carburetor and the intake manifold, the gasket being provided with a central opening for the passage of fuel mixture therethrough, and a wire screen carried by the gasket and having its portion covering the opening pressed out whereby to be V-shaped in cross section with the vertex of the V facing toward the stream of mixture.

2. A mixing device adapted for interposition between the flanged meeting ends of a carbureter and the intake manifold comprising a pair of gaskets provided with registering holes for the passage of securing bolts and provided with registering central openings, and a sheet of wire screen disposed 100 between the gaskets and covering said opening, the portion of the gauze exposed at the opening being pressed into angular shape with the vertex formed as a ridge to define diverging inclined portions, the ridge being 105 designed to be disposed toward the current of mixture passing through the device.

In testimony whereof I affix my signature,

HARRY A. VAN VLECK,
